(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with graphical user interface showing our new design; and,

FIG. 2 is a front view of a display screen with graphical user interface showing an alternative embodiment of our new design.

The broken line showing of the display screen and the remainder of the graphical user interface is for environmental purposes only and forms no part of the claimed design.

**1 Claim, 2 Drawing Sheets
(1 of 2 Drawing Sheet(s) Filed in Color)**

FIG. 1

FIG. 2
